(57) **CLAIM**

The ornamental design for a lacrosse stick, as shown and described.

DESCRIPTION

FIG. 1 is a side view of a lacrosse stick showing our new design;

FIG. 2 is an opposite view thereof;

FIG. 3 is a side view of another embodiment of a lacrosse stick showing our new design;

FIG. 4 is an opposite side view thereof;

FIG. 5 is a side view of another embodiment of a lacrosse stick showing our new design; and,

FIG. 6 an opposite side view thereof.

The broken lines in the Figures show environment for illustrative purposes only and form no part of the claimed design. The dot-dashed lines in the Figures show an indeterminate border around portions of the subject matter being claimed.
